UNITED STATES PATENT OFFICE.

PERL LEE STARR, OF CHICAGO, ILLINOIS.

GRINDING TOOL.

Application filed October 10, 1923. Serial No. 667,681.

This invention relates to new and useful improvements in abrasive instruments and more particularly to a grinding machine adapted for use in grinding and trueing the cylindrical surface of pistons used in various types of motors. The main object of my invention is the provision of a grinding instrument having the several parts thereof so constructed and arranged as to bring the abrasive or grinding elements into tight fitting contact with the cylindrical surface of the piston so that during the grinding action all uneven surfaces will be removed from the face of the piston and produce a surface which is entirely uniform throughout the circumference of the piston.

A further object of my invention is the provision of a piston grinding instrument wherein the abrasive or grinding elements are applied to the surface of the piston in such a manner that during the rotation of the piston in its grinding action the abrasive or grinding members will contact with the face of the piston in such a manner as to provide a shifting grinding movement which will tend to produce an entirely smooth and unbroken surface on the face of the piston.

With the above and other objects in view the invention consists in the novel features of construction, the combination and arrangement of parts hereinafter more fully set forth and shown in the accompanying drawings, in which:

Fig. 1, is a top plan view of a piston grinder constructed in accordance with my invention.

Fig. 2, is a side elevation.

Fig. 3, is a transverse section taken on the line 3—3, of Fig. 2, looking down onto the bottom supporting member.

Fig. 4, is a transverse section taken on the line 4—4, of Fig. 2.

Fig. 5, is a transverse section taken on the line 5—5, of Fig. 2.

Fig. 6, is a detail section taken on the line 6—6, of Fig. 1.

Fig. 7, is a detail perspective of the spring member applied to the pivotal connections of certain parts of the device for eliminating lateral movement.

In the construction of my improved device, I provide what will be known as a top and a bottom section, the bottom section comprising two semi-circular plates 1 and 2, the plate 2, having formed integral therewith an arm 3, which may be suitably secured to any stationary supporting element. As shown in the drawings the arm 3, is provided with spaced openings whereby bolts or other analogous fastening means may be used for attaching the machine to a stationary supporting element. 55

The plates 1 and 2, are normally retained in a paralleled plane by means of a heavy coil spring 5, one end of which is attached 65 to a perforated ear formed upon one face of the plate 1, and its other end detachably connected with the plate 2. From this it will be apparent that the two sections of the bottom member may be moved away from each other against the tension of the spring 5, but upon releasing the two sections that section 1, through the tension of the spring 5, will be moved back into position with respect to the stationary plate 2. 75

Formed integrally with the plate 1, and disposed at diametrically opposite points are the semi-circular bearing members 8 and 9, having outstanding pins 12, disposed below the horizontal plane of the bottom section 80 and the like bearing members 10 and 11, on section 2, are provided with the outstanding pins 13, which are disposed above the horizontal plane of the bottom section, said pins being disposed upon opposite sides of the center of the bottom section and connected by means of discs 14 and a diagonally disposed bar 14, which is retained in position upon the ends of the pins by means of cotter pins 15, and laterally held by a longitudinally bowed spring member 31.

From this arrangement it will be apparent that any movement of the section 1, with respect to section 2, will not only be upwardly but away from the section 2, and also 95 any movement of section 1, away from the stationary section 2, against the tension of the coil spring 5, will raise the section 1, above its horizontal alignment with the section 2. 100

The bottom section of the device which includes the plate 1 and 2, is provided with a plurality of sockets 16, which in the present instances are internally threaded to receive the horizontally disposed supporting bolts 17. In connection with the mounting of these bolts 17, I desire to have it understood that while I have shown and described the same as having a threaded connection with the sockets 16, other suitable connections may be used for supporting the bolts with respect to the plates 1 and 2. Mounted upon the bolts 17, are the upstanding supporting bars 18, which are arranged circumferentially of the bottom section. The lower ends of these bars are provided with suitable openings so that they may be loosely mounted for adjustment upon the bolts 17.

In order to provide for this adjustment 20 the suitable adjusting nuts 20, are arranged upon opposite sides of the bar whereby the adjustment of the nuts will move the lower ends of the bars either towards or away from the plates 1 and 2.

25 It will be apparent that the bolts 17, extend radially from the center of the bottom supporting members and the bars 18, will be moved toward and away from a central point.

30 The bars 18, in the present instance are each provided with a longitudinal projection 21, arranged intermediate the ends of the bars and formed with a groove 22, in which the grinding stones 23, are arranged.

35 The grinding stones are fitted within the grooves 22, so that a proper amount of the stone extends beyond the face of the projection for contact with the object to be ground.

40 In order to retain the grinding stones within the grooves 22, I provide suitable retaining members which in the present instance are shown in the form of set screws 24, which extend through the wall of the

45 grooves and have binding engagement with the stones which are arranged within the grooves.

The bars 18, are suitably connected at their upper ends by means of a top section 50 which is formed of two semi-circular members 25 and 26. The inner ends of each of these members are provided with enlarged portions 27 to form suitable bearing surfaces having their outer faces of substantially circular form when the ends of the two sections 25 and 26, are brought together. When the two members 25 and 26 are arranged with their meeting ends in abutting relation, they are disposed in a substantially 55 horizontal plane above and in spaced relation with the bottom portion of the device.

The member 25, is provided at each end with outstanding bearing pins 12' which are disposed below the horizontal center line of the upper section and the ends of the mem-

ber 26, are provided with the outstanding pins 13', which are disposed above the horizontal center line of the upper section and mounted upon the pins upon opposite sides of the section are discs 28, said discs being 70 provided with oppositely disposed openings to receive the pins. The discs 28, are retained in position upon the pins by means of the diagonally disposed connecting bars 29, the ends of which are mounted upon the pins and retained in place by means of suitable washers 30 and cotter pins 15.

In order to eliminate any lateral play on the part of the ends of the members 25 and 26, I insert between the discs 28 and the bars 29, a longitudinally bowed spring member 31' which is arranged transversely of each of the bars with its ends bearing against the surface of each of the discs at a point upon opposite sides of the pins 12' 85 and 13'.

It will be apparent from the construction and mounting of the top section that any movement imparted to the member 25, will tend to carry said member not only in a direction away from the member 26, but in a direction above the horizontal plane of the member 26, which movement is carried out simultaneously with the movement of the section 1 of the bottom supporting member. 95

The member 25, is returned to its former position with respect to the member 26, by means of the coil springs 32 each having one end connected to the perforated ears 33, on the member 25, at a point adjacent 100 each end thereof, while the other ends of the springs are connected to the perforated ears 34, formed on the member 26, at the point adjacent its ends. From this it will be apparent that the tension of the spring 105 members 32 which are arranged upon the inner faces of the members 25 and 26, will have a tendency to normally move the member 25 toward the member 26.

Extending diagonally through the members 25 and 26 and projecting radially from the center of the circle defined by the two members, are the supporting arms or bolts 35, and formed integral with each of the bolts are the hexagonal shoulders 36 which 115 are adapted for use in adjusting the bolts 35 toward and away from the center of the circle defined by the members 25 and 26.

The bolts 35 are threaded through suitable openings in the members 25 and 26, for adjustment with respect to the said members and are retained in various adjusted positions by means of the lock nuts 37, which are threaded onto the outer ends of the bolts and adapted to be forced into tight 125 engagement with the outer surface of the members 25 and 26 to retain the bolts against movement.

The upper ends of the bars 18 are provided with suitable openings for receiving 130

the inner ends of the bolts 35 and in mounting the bars upon the bolts they are preferably arranged in contact with one face of the shoulders 36 and retained against movement by means of the nuts 38 which are threaded upon the inner ends of the bolts and brought into tight engagement with one face of the bars. It will be apparent from this construction that the upper section 10 which includes the semi-circular members 25 and 26, and their co-operative parts is supported in spaced relation with the bottom section by means of the bars 18. It will also be noted that in view of the stationary support, of the member 2, of the bottom section, the bars which connect this member 2 with the member 26, tend to retain the member 26 against movement, whereas the connection between the member 25 and the member 1 of the bottom section will have a tendency to move these two members simultaneously carrying the grinding members supported thereby toward and away from the member which is being operated on by grinding members.

In order to prevent particles of abrasive and other material from coming in contact with the various connections, I provide suitable coverings which in the present instance are illustrated by dotted lines in Figures 1 and 3. These covers are preferably provided for the pivotal connections between the stationary and movable sections of the top and bottom portion of the device and may be formed of leather or other similar material and arranged over the parts so as to enclose the same sufficiently to prevent any of the flying particles from coming in contact with the pivotal connections.

In applying this device to a piston or other article to be ground it is essential that the piston be centrally arranged within the grinding device and prior to inserting the piston between the grinding members the sections 25 and 1, are moved in a vertical and lateral direction which will tend to move the grinding members designated in Fig. 1 as *a* and *b*, upwardly and outwardly with respect to the opposing grinding members *c* and *d*, thus leaving sufficient room to insert the piston or other member between the grinding members. After the piston has been placed in position between the grinding members the sections 1 and 25 are released and the tension of the coil springs 32 and 5, will have a tendency to exert an inward pulling movement upon the sections 1 and 25, and will move the grinding members *a* and *b* into contact with the outer surface of the piston and tend to clamp the piston between all the grinding members so that a uniform contact with the surface of the piston may be brought about.

After the piston or other member to be operated upon has been placed in position as

set forth above a rotary movement is imparted to the piston causing the surface of the same to travel over engaging portions of the grinding members. Particular attention is directed to the fact that as the surface of the piston is ground away the sections 25 and 1, not only have a tendency to move inwardly but also travel downwardly over the surface of the piston, bringing about a relatively vertically shifting movement over the surface of the piston, this together with the horizontal grinding action of the stationary members *c* and *d*, will tend to eliminate any unevenness on the surface of the piston, which has heretofore been caused in the grinding action of similar instruments.

In all of the grinding tools in use at the present time, as far as I know, the grinding elements are brought into direct contact with the surface to be ground, and through the rotary movement that occurs when grinding the surface, create a horizontal grinding action. This action causes, in the use of coarse stones as grinding elements, the production of an uneven surface on the face of the piston, in view of the fact that particles of the abrasive of which grinding elements are formed will travel in the same plane,

whereas, in my device, a varied grinding action is brought about so as to eliminate the forming of any uneven surface whatever on the face of the piston and produce a perfectly smooth unbroken surface. This smooth unbroken surface is produced, due to the fact that the grinding action of the stationary members and the movable members oppose each other in that the stationary grinding members are imparting a horizontal grinding movement, whereas the movable grinding members are creating a vertically shifting horizontal movement over the surface of the piston which will have a tendency to eliminate any scores caused by the stationary members and as the

surface of the piston is ground off and the diameter of the same reduced the grinding members *a* and *b*, will continue in their diagonal movement and this grinding action acting in opposition to the grinding action of the stationary grinding members produces a perfectly smooth and unbroken surface.

What I claim is:

1. A device for grinding a surface of revolution by rotation of the work or device, one with relation to the other, comprising two or more grinding tools having abrading surfaces adapted to lie in the surface of revolution of the work or device, means to support said tools with their abrading surfaces in said surface of revolution comprising two or more members, each carrying one or more of said tools and means to connect said members so that the members and the

- 4
- tool or tools each carry may move toward or from the axis of said surface of revolution but in so doing must move axially one member and its tool or tools with reference to another and the tool or tools of the latter.
- 5 2. A device for grinding a surface of revolution by rotation of the work or device, one with relation to the other, comprising two or more grinding tools having abrading surfaces adapted to lie in the surface of revolution of the work or device, means to support said tools with their abrading surfaces in said surface of revolution comprising two or more members, each carrying one
- 10 15 or more of said tools and means to connect said members so that the members and the tool or tools each carry may move toward or from the axis of said surface of revolution but in so doing must move axially one
- 20 member and its tool or tools with reference to another and the tool or tools of the latter, said means maintaining parallelism of said tools with said surface of revolution.
- 25 3. A device for grinding a surface of revolution by rotation of the work or device, comprising independent members, grinding elements carried by each member, means connecting the members to permit a limited separating movement thereof, said
- 30 35 means compelling a relative movement of the members at substantially right angles to the plane of and during such separating movement, and means to normally influence the members against such separating movement.
- 40 4. A device for grinding a surface of revolution by relative rotation of the work or device, comprising independent members which together form the substantially circular support, abrading tools carried by each member, yieldable means for normally holding the members together, and means connecting the members and operable in the separation of the members to permit a relative movement of the members in a direction at right angles to the axis of the support while at the same time compelling a relative movement of the members parallel to the axis of the support.
- 45 50 5. A device for grinding a surface of revolution by rotation of the work or device, comprising independent members which together form a substantially circular support, yieldable means for holding the members together, and connecting means between the members operating when the members tend to separate to compel a relative movement thereof which is a component of their movement at right angles to the axial line of the support and their movement parallel to such axial line.
- 55 60 65 6. A device for grinding a surface of revolution by relative rotation of the work or device, comprising a support formed at the lower end of semi-circular discs and at the upper end of semi-circular sections, springs arranged between the respective discs and between the respective sections to maintain a normal relation of the parts, bars connecting the discs and sections and formed to receive abrading elements, connectors tying the meeting ends of the discs together, connectors tying the meeting ends of the sections together, the mounting of the connectors relative to the discs and to the sections compelling a relative axial movement of the discs and sections under any tendency of the discs and sections to separate against the influence of said springs.
- 70 75 80 85 90 95 100 105 110 115 120 125 130
7. A grinding machine for pistons comprising a device to surround the pistons, said device being made up of two parts yieldingly connected, abrading elements carried by each part to engage the surface of the pistons, and connectors joining the respective parts and operative to compel a relative movement of the parts axially of the piston during any relative separation of the parts.
8. A grinding machine for pistons comprising a device to surround the pistons and made up of two yieldingly connected parts, abrading elements adjustably carried by said parts, connectors joining the parts to permit a limited separating movement thereof, said connectors bridging the juncture between the parts and being normally disposed at an inclination to the horizontal plane of the device, whereby in any tendency of the parts to separate or move together following the separation the connectors will compel a relative movement of the parts axially of the piston.
9. A grinding machine for pistons comprising a skeleton frame arranged to surround the piston and made up of two independent parts, springs connecting the parts and tending to normally draw the parts together, abrading tools carried by each part to engage the surface of the piston, pins projecting from the respective parts adjacent their point of juncture, the pins on one part being arranged on a plane above the pins on the other part, and rigid connectors movably engaging the pins, whereby in any tendency of the parts toward a relatively horizontal movement of the connectors compel a relative movement of such parts axially of the piston.
10. A grinding machine for pistons comprising a device to surround the pistons and including two semi-circular plates at the lower end and two semi-circular sections at the upper end, springs uniting the plates and sections to maintain them in normal contact on their diametric edges, bars connecting the united plates and sections, abrading elements carried by the bars to bear upon the piston, pins carried by the plates and by the sections adjacent their re-

spective meeting edges, the pins on one plate and its corresponding section being arranged on a plane above the plane of the pins on the remaining plate and its corresponding section, and connectors of rigid form loosely engaging the adjacent pins on the plates with similar connectors loosely engaging the adjacent pins on the section, the angular relation of the connectors com-

pelling a relative movement of the connected plates and sections axially of the piston in any tendency of such plates and sections to move against or under the influence of said springs.

In witness whereof, I hereunto subscribe my name this 6th day of Oct., A. D., 1923.

PERL LEE STARR.
